(57) **CLAIM**

The ornamental design for a vertical inverter busbar, as
shown and described.

DESCRIPTION

FIG. 1 is a perspective view of a vertical inverter busbar;
FIG. 2 is a left side view of the vertical inverter busbar
shown in FIG. 1;

FIG. 3 is a right side view of the vertical inverter busbar
shown in FIG. 1;

FIG. 4 is a front view of the vertical inverter busbar shown
in FIG. 1;

FIG. 5 is a rear view of the vertical inverter busbar shown
in FIG. 1;

FIG. 6 is a top view of the vertical inverter busbar shown in
FIG. 1; and,

FIG. 7 is a bottom view of the vertical inverter busbar shown
in FIG. 1.

The broken lines depict portions of the vertical inverter
busbar which form no part of the claimed design.
